JOB B. TILLEY, OF PENN YAN, NEW YORK.

WINDOW-SECURING DEVICE.

1,290,410.

Specification of Letters Patent. Patented Jan. 7, 1919.

Application filed March 13, 1918. Serial No. 222,181.

To all whom it may concern:

Be it known that I, Job B. Tilley, a citizen of the United States, residing at Penn Yan, in the county of Yates and State of New York, have invented certain new and useful Improvements in Window-Securing Devices, of which the following is a specification.

This invention relates to window securing devices, and more particularly to a securing device especially adapted for use in connection with car windows.

One of the main objects of the invention is to provide a securing device of simple construction and operation by means of which a window sash may be secured in vertical adjustment, this device also acting to positively lock the sash in its lower-most or closed position. A further object is to provide a securing device employing a spring pressed bolt engaging into socket members carried by the packing strip of the window casing, this bolt being so shaped as to permit the window to be adjusted even though the spring for normally forcing the bolt upwardly becomes broken or inoperative. A further object is to provide a lock of simple construction and operation which may be produced at small cost and may readily be applied to a window sash of standard construction. Further objects will appear from the detailed description.

In the drawings:

Figure 1 is a fragmentary front view of a securing device constructed in accordance with my invention as applied, part of the window casing being sectioned to show the sockets which coöperate with the lock,

Fig. 2 is a section taken substantially on line 2—2 of Fig. 1,

Fig. 3 is a section taken on line 3—3 of Fig. 1,

Fig. 4 is an underneath view of the lock detached from the window sash.

The window casing designated generally by A may be of standard construction, having the side beam 1 and bottom beam 2, a packing strip 3 being secured to the inner face of the side beam and forming a guide way for the window sash 4 which is slidable vertically in the frame in the usual manner. A lock, designated generally by 5 is secured on the lower rail of the sash. This lock is provided with a spring pressed bolt which engages into suitable socket members car-

ried by the strip 3 for securing the sash in vertical adjustment.

Lock 5 is provided with a substantially rectangular casing 6 having at its outer end an opening 7 through which projects the bolt 8. This bolt is provided with a reduced inwardly projecting stem 9 which is slideable through an aperture through the end wall 10 of the casing. An expansion coil spring 11 is mounted about stem 9 and is confined between end wall 10 of the casing and the inner end of the bolt 8. This expansion spring acts to normally hold the bolt in extended or projected position so as to project beyond the outer end of the casing. A finger knob 12 is provided with a reduced stem 13 which is operative in a slot 14 in the lower side wall 15 of the casing, this stem being secured in the bolt. Finger knob 12 serves to positively limit outward movement of the bolt in the casing, and also provides means whereby the bolt may be manually moved inwardly into the casing. A spacing block 16 projects inwardly from side wall 15 and coöperates with a similar block 17 provided at the forward end of side wall 18 of the casing to guide the bolt during its movement and prevent looseness or play of the bolt in the casing. Spacing block 16 is provided with an inwardly directed stud 19, block 17 being provided with a similar stud 20. These two studs are adapted to fit into suitable bores in the rails 6 of the sash when the casing is secured thereto by means of screws inserted through the openings 21 provided through the top of the casing so as to secure the block firmly in position. In practice, the lock is so positioned on the lower rail as to have the end thereof through which bolt 8 operates closely adjacent the inner face of the packing strip 3, as shown in Fig. 1 of the drawings.

The bolt is especially adapted to coöperate with socket members secured in the packing strip 3 in such a manner as to secure the sash in vertical adjustment so as to prevent downward movement thereof, some of the socket members being so constructed as to secure the sash positively against movement in either direction. In the drawings, I have shown but two of the socket members, though it will be evident that as many may be employed as desired. The upper socket member 22 is of substantially U-110

shaped, having the outer vertical arm 23, lower arm 24, and inner vertical arm 25. Outer arm 23 has its upper portion bent inward at an angle to provide an upwardly and inwardly inclined member 23^a, the upper edge of which is flush with the inner face of packing strip 3. The lower socket comprises a substantially rectangular recess 26 cut into strip 3, a reinforcing metal strip or bar 27 being provided at the upper edge of this recess. The outer end of bolt 8 is inclined upwardly and inwardly, as at 8^a and the bolt is provided at its outer end with an integral downwardly directed finger 8^b disposed at a right angle to the body of the bolt, the outer face of this finger forming a continuation of the outer end of the bolt, and being disposed at a slight angle thereto. The bevel at the outer end of the bolt is directed upwardly and inwardly. When the bolt is in extended position, it will project well within the socket members. When the outer end portion of the bolt is in the rectangular socket members formed by the recess 26, the upper face of the bolt will engage member 27 so as to positively prevent upward movement of the sash, finger 26 serving to effectually prevent any downward movement of the sash where such movement would be possible in a window construction which would permit the sash to be moved downwardly into the side of the car. When it is desired to raise the sash, bolt 8 is moved inwardly so as to disengage it from the lower socket member, after which the sash may be raised, the bolt being released and held in retracted position by engagement with the inner face of strip to bring the lower end of finger 26 above the upper end of flange 25 of socket member 22, it is forced outwardly by spring 11 into this socket member, finger 26 engaging behind the element 25 upon the sash being released, thus effectually securing the sash against downward movement. When the bolt is engaged into member 22, if it is desired to again raise the sash into a higher position, suitable members similar to member 22 being provided in a longitudinal series in strip 3, this may be readily accomplished by lifting the sash, the upward movement of the sash bringing the outer surface of finger 26 into engagement with the inner face of inclined element 23^a which thus acts to force the bolt into its casing, the bolt being retained in this position during the movement of the sash until the succeeding socket member is reached, when the bolt is again moved outwardly by spring 11 so as to secure the sash in the desired position. To lower the sash into its lowermost position, it is first raised to disengage the bolt from socket member 22, the bolt then being held in this position by means of knob 12 while the sash is lowered a suffi-

cient distance to bring finger 26 below element 25 of the socket member, after which the sash may be lowered the bolt being automatically forced into the lowermost socket when the window is in a lowered position, and serving to lock the window in this position in the manner previously described. This lock may be readily produced at comparatively small cost, and, because of the special shape of the locking end of the bolt, is well adapted for use in connection with car windows and similar structures. In the event of the spring 11 becoming broken or inoperative, the lock may be easily manipulated manually thus rendering it possible to adjust the sash which is not true of window locks now commonly used for this purpose.

When it is required to lower an elevated sash it is necessary to first raise the sash slightly so as to disengage the bolt from the socket member 22. This disengagement of the bolt cannot be effected without this raising of the sash as the bolt engages inside of the vertical arm 25 of the socket member. For this reason, danger of injury to a person due to releasing the lock when the sash is not grasped firmly is effectually eliminated, thus avoiding injuries which frequently result when window locks of ordinary construction are used in which the locks can be released so as to permit the sash to be dropped without first grasping the sash firmly so as to raise the same.

What I claim is:

1. In window adjusting means, the combination with a window casing and a sash adjustable therein, of a lock embodying a casing secured to said sash and provided through one end with a slot to accommodate a bolt, a bolt slidable in said casing and provided at its outer end with an integral angularly disposed finger, the slot corresponding in length to the combined width of the body of the bolt and the length of said finger so as to permit the outer end of said bolt to be moved into position to be flush with the end of the casing, means for normally holding the bolt in extended position so as to project beyond the end of the casing, means operable exteriorly of the casing for moving the bolt into inoperative position, and a socket member secured in said window casing for reception of the end portion of the bolt and having a substantially U-shaped upwardly directed body portion and an upwardly and inwardly inclined upper portion for forcing the bolt into the casing as the sash is raised.

2. A lock comprising a casing provided at one end, and at the approximate center of one side, with inwardly directed opposed blocks, said blocks co-operating to form a guide way for a bolt, a bolt slidably mounted in the casing and operable between said

blocks, said bolt being provided with a reduced rearwardly projecting stem operable through the end wall of the casing, an extension coil spring mounted about said stem 5 and confined between the body of the bolt and said end wall for normally forcing the bolt outwardly, said bolt being provided at its outer end with an integral locking finger disposed substantially at a right angle to 10 the body of the bolt, the distance between the block at the end of the casing and the outer side wall of the casing corresponding to the combined width of the bolt and length

of said finger so as to permit the bolt to be moved inwardly into the casing to bring 15 the outer end thereof flush with the end of said casing, and means operable exteriorly of the casing for moving the bolt into retracted position, said means serving to positively limit inward movement of said bolt. 20

In testimony whereof I affix my signature in presence of two witnesses.
